Primary Examiner — Paula Allen Greene*(74) Attorney, Agent, or Firm* — Amin, Turocy & Watson LLP(57) **CLAIM**

The ornamental design for a headphone, as shown and described.

DESCRIPTION

FIG. 1 is a front, bottom and right side perspective view of a headphone showing our new design;
FIG. 2 is a front elevational view thereof;
FIG. 3 is a rear elevational view thereof;
FIG. 4 is a top plan view thereof;
FIG. 5 is a bottom plan view thereof;
FIG. 6 is a right side elevational view thereof; and,
FIG. 7 is a left side elevational view thereof.
The portions of all drawings shown in broken lines are for illustrative purposes only and the broken lines form no part of the claimed design.

1 Claim, 7 Drawing Sheets(56)
